BOTTLE AND LIKE CONTAINER

John Blandy Llewellyn, Westbourne Grove, London, England, assignor to Jerome Taishoff, London, England

Application February 1, 1935, Serial No. 4,580
In Great Britain February 6, 1934

7 Claims. (Cl. 120—64)

This invention relates to bottles or containers and more especially to devices for effecting removal of the liquid contents of a bottle or other container in increments or doses which devices 5 also form closures for said container.

Devices for this purpose have in general included a diaphragm adapted to be depressed into the air space above the liquid content of the bottle so as to compress the air and to displace a dose 10 of liquid, and a well or other receptacle, hereinafter termed "a well", which receives the liquid dose thus displaced. The present invention relates particularly to devices of this character.

It is one object of the invention to provide 15 an improved device of this character which will readily supply the required liquid dose even under the varying conditions met with in practice such as variation in the liquid content of the bottle, variations in room temperature and the like.

20 A further object of the invention is to provide a construction wherein the actuation of the diaphragm is more effectively controlled and wherein the diaphragm and the well associated therewith are constructed so as to provide a maximum of movement with minimum strain of 25 the diaphragm. Another object is to provide a construction of device of the abovementioned character which is of compact form so as to occupy only about the same space as a closure 30 of normal construction.

Other features of the invention will be apparent from the following description.

In the accompanying drawing, which shows by way of example several forms which the invention 35 may take:

Fig. 1 is a vertical section of a bottle in association with a well and diaphragm, the latter being in their normal raised position.

Fig. 2 is a view of a bottle similar to Fig. 1 40 showing the well and diaphragm depressed, whereby the well is partially filled with liquid from the bottle.

Fig. 3 is a view on an enlarged scale of a detail shown in Figs. 1 and 2.

45 Figs. 4 and 5 are views showing another arrangement in its normal and operative positions respectively, and

Figs. 6 and 7 are similar views of another modified form.

50 Like reference numerals indicate corresponding parts in all the figures.

In the forms shown in Figs 1 and 2 the bulk container for the ink or other liquid takes the form of a bottle 1 having a relatively wide neck 55 2 which is screwed externally at 3 and in which

the well 4 is axially disposed, the said well being secured to the bottle in a fluid-tight manner by means of an annular flange 5 forming part of a resilient diaphragm 6 formed or provided on the well 4. This flange or diaphragm 5 is adapted to seat itself upon the upper edge 7 of the neck of the bottle and to be secured by means of a cap 8 having a downwardly depending portion 9 which is pressed to define an internal screw, the internal screw being adapted to engage the external screw 10 on the neck of the bottle, whereby the inwardly projecting annular flange 10 of the cap is adapted to press on the part 5 of the diaphragm and thus maintain the said well and diaphragm in fluid-tight engagement with the bottle. 15

The lowest internal part of the well 4 is apertured and provided with a tube 12 through which the liquid in the bottle is adapted to pass upward to the well 4; the free end of the tube is located in the lowest position in the interior of the bottle whereby the whole of the liquid in the bottle can be passed to the well. The well 4, however, projects upwards from the diaphragm 6 to define an annular ledge 13 on which a second cap 14 is adapted to bear, this cap having a downwardly extending portion 15 which is screwed at 16 to engage an external screw on the inner cap 8. 20

A metal rubbing washer 17 to diminish the friction due to relative movement of the parts is interposed between the upper face of the annular ledge 13 and the annular face of the external cap 14. The upper end 18 of the well is preferably formed with a bead which, with the annular ledge 13, defines a groove 19 into which the inner edge of the external cap 14 is adapted 25 to project to limit the movement of the said cap, the arrangement of parts being such that the rotation of the external cap 14 over the fixed inner cap 8 depresses the diaphragm 6 inwards and thereby reduces the capacity of the interior of the bottle 1 to cause a portion of the fluid in the bottle to pass upward into the well. Conversely, by rotating the external cap 14 in the reverse direction, the diaphragm 6 rises and any liquid remaining in the well 4 is caused to pass downward into the bottle. A valve washer 20 (see Fig. 3) is located in the well 4 and rests on a ledge formed in the well 4 and rests on a ledge 30 formed in the well where the washer is spaced apart a short distance from the bottom, the said washer being provided with one or more apertures 21 offset from the aperture in the well and communicating with the tube 12, by which means squirting or splashing of the liquid during its passage from the tube 12 to the well 4 is avoided. 35

This valve washer 20 may also act as a stopper or 40

closure by the addition of a suitable plug (not shown) inserted in the body of the well and adapted to press on the washer for example of the type shown in Fig. 4 but of sufficient axial extent to contact washer 20. In cases where the tubular member 12 communicates with an aperture in the side wall of the well at the lowest part thereof, this valve washer 20 may be dispensed with, as the ink or other liquid, on leaving the tubular member 12, will impinge on the side wall of the well.

Figs. 4, 5, 6 and 7 illustrate other applications of the invention wherein the inner cap is non-removably secured to the bottle by so forming the cap that the lower free edge is adapted to be turned inwards to overlap the lower annular portion of the neck of the bottle.

In Figures 4 and 5 the bottle 1 is shown having its neck 2 formed with a plain annular thickened portion 36, the well 4 and its associated diaphragm 6 being secured in a fluid-tight manner within the neck 2 by a cap 37, the lower free edge of which is turned inwards as at 38 to non-removably secure the cap to the bottle. The well 4 is provided with a shoulder 39 on which a second cap 40 is adapted to bear. The shoulder 39 may be provided with a metal rubbing washer 17 as described with reference to Figs. 1 and 2. This second cap has a dependent substantially cylindrical portion 41, the free edge of which is rolled to form a bead 42 in relation to which the cylindrical wall of the second cap is medially disposed, the inner part of the bead thus forming an inwardly directed lip round the free edge of the cap.

The inner cap 37 and the outer cap 40 are provided with substantially vertically disposed co-operating projections 44 and recesses 45 respectively, so formed that when the projections and recesses are in engagement with each other the cap 40 may be moved freely in a vertical direction only relative to the cap 37, but when the cap 40 is depressed to such an extent that the rim 42 of the cap comes below the lower ends of the projections 44, the cap 40 can then be partially rotated to cause the lower edge of the projections 44 to engage the edge of the cylindrical head and the cap is thereby retained in the depressed position.

A stopper 47 may be provided to close the top of the well 4.

In the modification illustrated in Figures 6 and 7, the cap 37 engages at the inner edge of its annular top face with the vertical cylindrical surface 49 of the shoulder 39, and the second cap 40 fits into a groove formed between the shoulder 39 and a bead 48 surrounding the mouth of the well 4. The well is emptied or filled by raising or lowering the cap 40, as the case may be, to operate the diaphragm. The well is adapted to be retained in the desired position by the frictional grip between the cylindrical face 49 and the inner edge of the annular top face of the cap 37.

I wish it to be understood that in all the forms of bottle hereinbefore described the well may be fitted with a washer 20, arranged and operating in a similar manner to that described with reference to Fig. 3, or alternatively, the tubular member may be so disposed that its upper end communicates with an aperture in the side wall of the well, whereby the ink or other liquid will be ejected in a lateral direction.

Further, while the well and diaphragm are preferably made of rubber, the well can be made of synthetic resin or similar mouldable material

and the diaphragm can be made wholly or partially of any suitable resilient material, or may be of rigid material resiliently connected to the well and/or the bottle. The diaphragm may be formed integral with the well or separately therefrom and subsequently secured thereto, in which latter case, thin metal may be employed resiliently connected to the body of the well with or without the provision of a washer to ensure air and fluid-tightness between the diaphragm and the upper part of the bottle. The caps may be formed of metal, synthetic resin or other rigid material.

The bottles and caps may be of any suitable shape depending upon practical and/or aesthetic requirements.

What I claim and desire to secure by Letters Patent is:—

1. In a bottle or container for liquids a device for effecting removal of the liquid contents of said container in doses which comprises a diaphragm contacting the air above said liquid content for effecting displacement of a liquid dose by compression of said air, a well adapted to receive said liquid dose supported by said diaphragm so as to move therewith and a manually operable actuating device positively engaging the walls of said well and displaceable at right angles to the plane of said diaphragm.

2. In a bottle or container for liquids a device for effecting removal of the liquid contents of said container in doses which comprises a diaphragm disposed above the liquid contents, a well in communication at its lower end with the liquid space of said container supported by said diaphragm to move therewith and a cap member covering said diaphragm in positive engagement with the walls of said well and manually displaceable at right angles to the plane of said diaphragm to effect a positive movement of said diaphragm in opposite directions.

3. In a bottle or container for liquids a device for effecting removal of the liquid contents of said container in doses which comprises a diaphragm disposed above the liquid contents, a well in communication at its lower end with the liquid space of said container supported by said diaphragm to move therewith, a supporting surface on said container and a movable cap member in threaded engagement with said supporting surface and connected to the walls of said well so as to allow free rotation of said cap member relatively to said well and to ensure common axial movement with said well.

4. In a bottle or container for liquids, a device for effecting removal of the liquid contents of said container in doses comprising a diaphragm disposed above the liquid contents, a stationary element securing the edges of said diaphragm to said container and provided with a supporting surface, a well communicating at its lower end with the liquid space of said container, connecting means between said diaphragm and said well, and a cap member in engagement with said supporting surface and longitudinally displaceable relatively thereto, said cap member positively engaging said well.

5. In a bottle or container for liquids, a device for effecting removal of the liquid contents of said container in doses comprising a diaphragm disposed above the liquid contents, a stationary element securing the edges of said diaphragm to said container and provided with a supporting surface, a well communicating at its lower end with the liquid space of said container, connect-

ing means between said diaphragm and said well, and a cap member in engagement with said supporting surface and with said well and longitudinally displaceable relatively to said surface so as to move said diaphragm from a position above the plane of its gripped edges to a position below said plane.

6. In a bottle or container for liquids a device for effecting removal of the liquid contents of said container in doses which comprises a diaphragm disposed above said liquid contents, means to secure the edges of said diaphragm to said container, a well supported by said diaphragm and having an orifice at its lower end, a flexible tube communicating with said orifice and with the liquid content of said container, a baffle washer disposed within said well above said orifice and a manually operable actuating device

for positively moving said diaphragm in opposite directions.

7. In a bottle or container for liquids a device for effecting removal of the liquid contents of said container in doses which comprises a diaphragm disposed above said liquid contents, means to secure the edges of said diaphragm to said container, a well supported by said diaphragm so that the major portion of the body of said well projects below said diaphragm and provided with an orifice at its lower end, a flexible tube communicating with said orifice and with the liquid content of said container, a baffle washer disposed within said well above said orifice and a manually operable actuating device for positively moving said diaphragm in opposite directions.
